UNITED STATES PATENT OFFICE

155,800

DESIGN FOR A PAPER TESTER

Raymond E. Getchell, Holyoke, Mass., assignor to
B. F. Perkins & Son, Inc., Holyoke, Mass., a corporation

Application June 30, 1948, Serial No. 147,315

Term of patent 14 years

(Cl. D52—1)

To all whom it may concern:

Be it known that I, Raymond E. Getchell, a citizen of the United States, residing at Holyoke, in the county of Hampden and Commonwealth of Massachusetts, have invented a new, original, and ornamental Design for a Paper Tester, of which the following is a specification, reference being had to the accompanying drawings, forming part thereof:

Fig. 1 is a side elevational view of a paper tester showing my new design;

Fig. 2 is a front elevational view of the paper tester shown in Fig. 1; and

Fig. 3 is a rear elevational view of the paper tester shown in Figs. 1 and 2.

I claim:

The ornamental design for a paper tester, as shown.

RAYMOND E. GETCHELL.
